Primary Examiner—Doris Clark

[57] CLAIM

The ornamental design for an internally illuminated lighting track, as shown and described.

DESCRIPTION

FIG. 1 is a perspective view of a first embodiment of an internally illuminated lighting track showing my new design;

FIG. 2 is a transverse cross-sectional view thereof; taken along section line 2—2 of FIG. 1; and,

FIG. 3 is a perspective view of a second embodiment of an internally illuminated lighting track showing my new design.
